MUSIC LEAF TURNER

Filed April 6, 1926

2 Sheets-Sheet 2

UNITED STATES PATENT OFFICE.

CHARLES L. KNAPP, OF SHENANDOAH, PENNSYLVANIA.

MUSIC-LEAF TURNER.

Application filed April 6, 1926. Serial No. 100,108.

My present invention pertains to music leaf turners, and contemplates the provision of a music leaf turner that is reliable in operation and is adapted to promptly bring about the turning of a leaf following slight pressure on a finger piece.

With the foregoing in mind, the invention in all of its details will be fully understood from the following description and 10 claims when the same are read in connection with the drawings, accompanying and forming part of this specification, in which:—

Figure 1 is an elevation, partly in section, of the music leaf turner constituting the 15 best practical embodiment of my invention of which I am cognizant.

Figure 2 is an enlarged fragmentary horizontal section taken in the plane indicated by the line 2—2 of Figure 1, looking up- 20 wardly.

Figure 3 is an enlarged fragmentary section taken in the plane indicated by the line 3—3 of Figure 1, looking toward the left.

Figure 4 is an enlarged vertical section 25 taken in the plane indicated by the line 4—4 of Figure 3, looking toward the right.

Figure 5 is a perspective of the lowermost swingable member comprised in my improvement.

Similar numerals of reference designate 30 corresponding parts in all of the views of the drawings.

Shown in Figures 1 and 2 is a bar 1, equipped at its ends with appurtenances 2 35 of appropriate description, whereby the said bar may be attached to a piano, organ, music stand or any other desired support.

Appropriately fixed with respect to the bar 1 is a casing 3, and guided and movable rectilinearly in one wall of the said casing is a rod 4 having a finger piece 5 at its outer end. The rod 4 is pivotally connected at 6 to a keeper 7, having a beveled toe 8, Figure 2, the said keeper 7 and the 40 inner portion of the rod 4 being arranged between fixed bracket members 9 in the casing 3, Figure 4, and the said keeper 7 having lateral projections 10, disposed and movable in slots 11 in the said brackets 9. A spring strip 12 is fixed at 13 in and to the casing 3 and the free portion of said spring strip 12 extends and is adapted to play between the bracket members 9 and is disposed against and back of the keeper 7 as made clear in 45 Figures 2 and 4. It will also be understood from Figure 2 that an expansion spring 14

is interposed between an abutment 15 on the rod 4 and a washer or other suitable abutment 16 arranged against the edges of the bracket members 9, the said spring 14 being 60 designed to return the rod 4 to and retain said rod 4 yieldingly in the normal position shown in Figure 2, and in this connection it will be understood that the return of the rod 4 to the normal position shown in Figure 65 2 will be attended by the return of the keeper 7 to its normal position also shown in Figure 2. When the rod 4 is moved inwardly or in the direction of the adjacent arrow in Figure 2, the keeper 7 will be rocked against the spring strip 12 and will be moved inwardly until its projections 10 bring up against the inner end of the slots 11, whereupon the keeper 7 will be swung in the direction indicated by the arrow thereon in Figure 70 2, and, as before stated, the release of the finger piece 5 will be attended by the immediate return of the keeper 7 to the normal position shown in Figure 2.

The casing 3 is also provided with an interior fixed stop 20 and an interior and fixed bracket 21, the said bracket 21 being provided with a plurality of apertures 22 as appears in Figure 3. Hooked in the apertures 22 of the bracket 21 or otherwise suitably connected to the said bracket 21 are 75 spring strips 23 which are arranged one above the other in spaced relation as shown in Figures 3 and 4.

Journaled in appropriate bearings in the lower and upper walls of the casing 3 is an upright shaft 24, and surrounding and movable independently of the shaft 24 and of each other is an inner sleeve 25 and an outer sleeve 26, the inner sleeve 25 terminating at its lower end at an intermediate point between the lower and upper walls of the casing 3, and the outer sleeve 26 terminating at its lower end at a higher point in the casing 3 and between the lower and upper 100 walls of the casing.

Each of the elements 24, 25 and 26 is provided at its upper end with an arm, and each arm is equipped with a clip of appropriate construction designed to take hold of the upper edge portion of a leaf of music. The said arm of the shaft 24 is numbered 24^a, and its clip is numbered 24^b, and the arm of the inner sleeve 25 is numbered 25^a and the clip on said arm is numbered 25^b 105 and the arm on the outer sleeve 26 is numbered 26^a, the clip carried by the said arm

26^a being disposed back of the clip 24^b in Figure 1 and therefore not shown.

Disposed and movable swingably in the casing 3 is the swingable element 34 complementary to the shaft 24. By comparison of Figures 4 and 5 the said swingable element 34 will be understood as comprising a lower disk-like portion 36, a sleeve 37, and an upper plate 38, the sleeve 37, disk 36 and plate 38 being fixed together, and the sleeve 37 being splined or keyed or otherwise appropriately fixed to the shaft 24 so that the element 34 and the shaft 24 will turn in concert. It will also be understood that the plate 38 is provided with an abutment 39 to bring up against the stop 20, and is also provided with a pendent arm 40 for cooperation with the toe 8 of the keeper 7, and it will further be noted that the said pendent portion 40 is provided with a lateral projection 41, Figures 3 and 5, for a purpose hereinafter set forth. Superposed upon the plate 38 of the swingable element 34 and fixed to the inner sleeve 25 is a swingable member 45 which is generally similar to the swingable element 34 with the exception that its pendent portion 40^x, Figure 4, is longer than the pendent portion 40 so as to reach down to the horizontal plane of the keeper 7, and also with the exception that its pendent portion 40^x, Figures 2 and 4, is not provided with any projection like the projection 41 of the element 34.

The swingable element 55 of the outer sleeve 26 is fixed to said sleeve 26 and is generally similar in construction to the swingable element 34 except that its pendent portion 40^y is sufficiently long to reach down to the horizontal plane of the keeper 7, and also with the exception that the said pendent portion 40^y is provided with a lateral projection 41^y reversely arranged to the projection 41, as clearly appears in Figure 2.

Manifestly when the several arms of the elements 24, 25 and 26 are arranged as shown in Figure 1, the swingable elements 34, 45 and 55 will be relatively arranged as shown in Figure 2, and the toe 8 of the keeper 7 will rest in position to hold the member 55 against movement in the direction indicated by the series of arrows at the left of Figure 2, and the projections 41 and 41^y will operate to maintain the pendent portions of the three swingable elements in spaced relation. At this point I would have it understood that there is one of the springs 23 to each of the three swingable elements described, the ends of the springs 23 remote from the bracket 21 being connected in appropriate manner to the swingable elements so that following the release of each swingable element from the keeper 7, the spring of said element will promptly swing the element until the same brings up against the stop 20. Incident to the said swinging move-

ment of each element the shaft 24, the inner sleeve 25 or the outer sleeve 26, as the case may be, will be swung from the position shown in Figure 1, forwardly and toward the left so as to adequately turn a leaf of music.

The parts of my improved device are shown in corresponding positions in Figures 1 and 2, and from this it follows that the initial inward movement of the rod 4 will be attended by the release of the swingable member 55 complementary to the outer sleeve 26 whereupon the leaf connected with the sleeve 26 will be turned, and manifestly following the release of the swingable element 55, and the release of the rod 4, the toe 8 of the keeper 7 will snap into position to constitute an abutment for the pendent portion of the swingable element 45 so as to hold the inner sleeve 25 against turning. When, however, the rod 4 is moved inwardly, the second time, the pendent portion of the swingable element 45 will be released from the toe 8 of the keeper 7, and when said rod 4 is released, the keeper 7 will assume a position to enable its toe 8 to offer an abutment to the pendent portion of the swingable element 55 and thereby preclude turning of the outer sleeve 26 until the third inward movement of the rod 4, whereupon the third leaf of music will be turned. The several sweeps or arms carrying the devices for engaging leaves of music are designed to be returned to the position shown in Figure 1 by hand, and when the said sweeps or arms are so returned, the pendent portions of the swingable elements will, by virtue of the beveled toe 8, ride past the said keeper 7 and assume the positions shown in Figure 2.

It will be apparent from the foregoing that my novel device is reliable in operation and is well adapted, in general, to withstand the usage to which music leaf turners are ordinarily subjected; and it will also be noted that my novel device is compact, and that when nickel plated or otherwise embellished the device will be calculated to enhance rather than detract from the finished appearance of a piano, organ or the like.

While I prefer the construction and relative arrangement of the elements of my improvement as disclosed herein, I do not desire to be understood as limiting myself to the precise construction and relative arrangement of the parts in the disclosure, my invention being defined by my appended claims within the scope of which modifications may be made without departure from my invention.

Having described my invention, what I claim and desire to secure by Letters-Patent, is:—

1. A music leaf turner comprising a casing, a shaft, and inner and outer sleeves sur-

rounding said shaft and all journaled in and extending from the casing, sweeps carried by the shaft and the inner and outer sleeves and equipped with means for the connection 5 with the same of leaves of music, superposed swingable devices disposed in the casing and fixed to the shaft, the inner sleeve and the outer sleeve, respectively, said swingable devices having lower disc-like portions, upper 10 plates and means connecting the disc-like portion and upper plate and also having pendent portions of different lengths on said plates and the said pendent portions being arranged to normally rest in spaced relation and two 15 pendent portions being provided with reversely arranged projections disposed toward the other pendent portion, springs for moving the said swingable devices, a stop for limiting the movement of said devices under 20 the action of their springs, and a manually controlled spring influenced keeper having a beveled toe to engage the pendent portions of the swingable devices.

2. A music leaf turner comprising an attaching bar, a casing fixed on said bar, a shaft, and inner and outer sleeves surrounding said shaft and all journaled in and extending from the casing, sweeps carried by the shaft and the inner and outer sleeves and 25 equipped with means for the connection of the same to leaves of music, swingable devices disposed in the casing and fixed to the shaft, the inner sleeve and the outer sleeve,

respectively, said swingable devices being superposed and having pendent portions of 35 different lengths and the said pendent portions being adapted to normally rest in spaced relation and two pendent portions being provided with reversely arranged projections disposed toward the other pendent 40 portion, springs for moving the said swingable devices, a stop in the casing for limiting the movement of said devices under the action of their springs, a bracket fixed in the casing and having a slot, a spring strip connected to the casing and disposed alongside said bracket, a keeper having a beveled toe to engage the pendent portions of the swingable devices and also having a projection disposed in said slot of the bracket, and further having its heel end opposed to the said 45 spring strip, a rod guided in a wall of the casing and pivotally connected to the said keeper, and a spring of expansion type surrounding said rod and interposed between 50 an abutment thereon and an inner stationary abutment; each of the said swingable devices having an upper disk and a plate in spaced and parallel relation and joined by a sleeve and each also having its pendent portion integral with its upper plate, and the 55 projections on the pendent portions being integral with the said pendent portions.

In testimony whereof I affix my signature.

CHARLES L. KNAPP.
